UNITED STATES PATENT OFFICE.

EMIL WEITZEL, OF PHILADELPHIA, PENNSYLVANIA.

PRINTER'S GALLEY-LOCK.

1,140,728.

Specification of Letters Patent.

Patented May 25, 1915.

Application filed September 1, 1914. Serial No. 859,617.

To all whom it may concern:

Be it known that I, EMIL WEITZEL, a citizen of the United States, and a resident of Philadelphia, in the county of Philadelphia and State of Pennsylvania, have invented a certain new and useful Printer's Galley-Lock, of which the following is a specification.

My invention relates to improvements in the method and means for locking a column of type in a printer's galley.

Ordinarily after type has been set up in the galley, in a column of a given length and of a given width, a plate is placed on top of the column and a chaser is inserted by means of which the column is forced against one wall of the galley, and the column is locked by a number of quoins which are wedged in between the chaser and the adjacent wall of the galley. To make corrections it becomes necessary to remove the quoins. Furthermore, it is necessary to have a large supply of quoins to fill in the space between the column and the wall of the galley, which space varies with the width of the column.

The chief object of this invention is to provide a lock adapted to replace the chaser and quoins, capable of adjusting itself to columns of different width, which releases the column when the lock is subjected to a pressure exerted by the fingers of the compositor, and when said pressure is released it immediately locks the column in the galley.

With these and related objects in view, this invention comprises the method and means hereinafter described, a preferred form of which is illustrated in the accompanying drawing, and embraced within the scope of the appended claims.

In the said drawing, Figure 1 is a plan view of my lock in connection with a galley having a column of type locked thereby; Fig. 2 is a fragmentary plan view of the lock shown to be compressed; Fig. 3 is a section on the line 3—3 of Fig. 1, and Fig. 4 is a section on the line 4—4 of Fig. 1.

Referring more particularly to the drawing for a detail description of my invention, 1 and 2 represent the side bars of the lock, 3 represents a tension spring between the bars, 4, 4 represent floats each being connected to an end of the spring in opposition to the other. Each float is pivotally connected by two pairs of levers 5 and 6 with

the bars 1 and 2. Each float is provided with a slot forming a path for a pin 7. The pin constitutes a floating pivot for a pair of levers 8, which are pivotally connected with the levers 6 at the bars 1 and 2. Each bar is provided at its ends with finger grips 9. The bar 1 carries a runner 10 on which is pivoted a handle provided with a cam 11 and adapted to lock the runner along the bar. 12 represents a printer's galley, 13 a column of type, and 14 a blank between the column and the runner.

The *modus operandi* is as follows:—Assume that the type is set up in the form of the column shown in Fig. 1. To lock the column, take hold of the finger grips 9 and compress the lock as shown in Fig. 2. Insert the lock in the galley and release the fingers. The spring 3 contracts and causes the floats to move in opposite directions, which movement is transmitted by the system of levers to the bars 1 and 2, whereby the bar 2 is forced against the adjacent wall of the galley and the bar 1 against the adjacent side of the column, and the column becomes tightly wedged against its adjacent side of the galley. The runner is then released by moving the handle of the cam in a direction away from the runner, and the runner is then free to be moved against the blank on top of the column when the cam is turned in the position shown in Fig. 1 to lock the runner on the bar. To make any corrections or other necessary changes in the column, the runner is released and the bar 1 is forced away from the type, which operation may be performed with one hand, leaving the other hand free to make the necessary changes.

Having thus described my invention, what I claim as new and desire to protect by Letters Patent, is—

1. A galley lock comprising a pair of bars, a spring, a float at each end of the spring, and a system of levers connecting the floats with the bars.

2. A galley lock comprising a pair of bars, a spring between the bars, a float connected at each end of the spring, and means pivotally connecting the floats with the bars.

3. A galley lock comprising a pair of bars, a spring between the bars, a float at each end of the spring, a pair of levers pivotally connected at each float, and levers pivotally connecting each float with the bars.

4. A galley lock comprising a pair of

bars, a spring, a pair of floats, a pair of levers pivotally connecting the bars with each float, and a pair of levers pivotally connected with the bars and connected together by a floating pivot.

5. A galley lock comprising a pair of bars, means yieldingly holding the bars apart, a runner carried by one of said bars, and means for clamping the runner along the 10 bar.

6. A galley lock comprising a pair of

bars, yieldable means adapted to force the bars apart, said bars provided with means whereby they can be moved in opposition to the forcing means.

15 In testimony whereof I have signed this specification in the presence of two subscribing witnesses.

EMIL WEITZEL.
